PARTITIONED FOUNTAIN ROTARY INTAGLIO PRINTING MACHINES

Charles A. Harless, Riverside, Conn., assignor to R. Hoe & Co., Inc., New York, N. Y., a corporation of New York

Application May 22, 1951, Serial No. 227,637

4 Claims. (Cl. 101—157)

This invention relates to rotary intaglio printing machines.

More particularly, the invention is concerned with partitioned ink fountain structures for such machines, it being an object of the invention to provide an improved arrangement for supplying different inks to different lengthwise portions of an intaglio printing cylinder.

A preferred embodiment of the invention will now first be described with reference to the accompanying drawing and the features forming the invention will then be pointed out in the appended claims.

In the drawing:

Figure 1 is a plan view of a fountain embodying the invention in a preferred form;

Figure 2 is a side elevation, partly in central vertical section, of the fountain of Figure 1;

Figure 3 is a section on the line 3—3 of Figure 2;

Figure 4 is a section similar to Figure 3, but showing certain parts in different positions;

Figure 5 is a detail elevation view of a sealing ring, partly broken away;

Figure 6 is a section on the line 6—6 of Figure 3;

Figure 7 is a fragmentary view looking in the direction of the arrows 7—7 of Figure 5;

Figure 8 is a section on line 8—8 of Figure 7; and

Figure 9 is a section on line 9—9 of Figure 5.

The printing cylinder 1 is supported in bearings 2 carried by the usual press frames 3 which also support the fountain 4 in inking relation to the cylinder. The doctor mechanism is generally of the type shown in Harless application Serial No. 65,155, filed December 14, 1948 for Rotary Intaglio Doctor Mechanism, now U. S. Patent No. 2,644,394. Arms 5 are pivotally mounted on the axially reciprocating slide 6 by means of shaft 7, and support a bar 8 which carries the doctors. Two doctors are provided, one for each end of the cylinder. The doctor structure is shown in Figures 1, 3 and 4, only the left hand doctor being shown in place in Figure 1, and the right hand doctor of that figure, which is identical, being removed to show the fountain structure more clearly. Each doctor comprises a blade 9 held by the upper and lower clamp elements 10 and 11 of the doctor blade holder. The holder is fixed in the bar 8 by means of an angle on the element 11 which fits in a groove in the bar as shown in Figures 3 and 4 and is held therein by clips 12 detachably secured to the bar 8.

The cylinder 1 has a central section or neck 19 (Figure 2) of reduced diameter and the fountain is provided with a partition and sealing means cooperating with the neck 19 to divide the fountain into two compartments. A split sealing ring which is shown in detail in Figures 5 to 9, comprises upper and lower half-rings 21 and 22. These are formed with internal circumferential grooves 23 which receive resilient strips 24 for sealing to the neck 19 of the cylinder. A number of pins 25 (Figure 9) are provided for holding the strips 24 in place.

2

Externally the half-rings 21—22 have flanges 26 fitting around the fountain center partition members, and grooves 27 (Figure 9) for resilient strips 28 (Figure 6), which seal the half-rings 21—22 to the partition.

The fountain center partition includes a lower part 30 which may be cast integral with the fountain body and has a semicircular seat 31 (Figure 2) for the (lower half) ring 22, the seat 31 being received between the flanges 26 of the half-ring 22 and being sealed to the 10 half-ring by the resilient strips 28. Above the center line of the cylinder, the partition 30 is formed to receive an upper partition member 32 (Figure 4) which cooperates similarly with the upper half-ring 21 and is detachably fastened to the part 30 by means of strips 15 33 screwed to member 32 and overlapping the part 30, thus completing the center partition as shown in Figures 3 and 4. Half-ring 22 is secured to the partition member 30 by means of pins 34 (Figure 4) in holes 35 (Figure 7). Lubrication is provided for by means of 20 fittings 36 in the member 32 (Figures 1 and 4) and channels 47 passing through the ring 30 (Figures 7 and 8).

The upper partition member 32 is formed with arcuate flanges 40 overlapping the cylinder 1 at each side of the neck 19 (Figures 1, 2 and 4) and spaced from the cylinder surface by only a small clearance so as to catch any ink thrown off the end of the cylinder, and keep it in the fountain. A pair of covers 41 (Figures 2, 3 and 4) are pivoted to the fountain wall and have end flanges 43 (Figure 4) conforming to the arc of the flanges 40 and overlying the same. Plates 44 carried by the covers 41 extend down close to the cylinder surface when the covers are in closed position and are notched as at 45 to fit the flanges 40. The opposite end of each cover is similarly related to an arcuate end cap 46 (Figure 2) overlapping the end of the cylinder 1. It will be understood that the caps 46 and cooperating structure provide an effective closure at the cylinder ends. This structure in itself, however, forms no part of the present invention and, being well known, will not be described herein. Plates 47 (Figure 4) mounted on the partition member 30 extend over the upper partition member 32 and bolts 48 when tightened, hold it in place.

At the doctor side of the fountain, a pivoted cover 45 50 (Figures 3 and 4) is provided. This cover is equipped with a sealing blade 51 for each end of the fountain, and the blades extend to a central barrier 52. The cover 50 also carries a shield 53 fitting in a notch 54 in the flange 40 and with its barrier 52 fits the upper partition 32 and the flange, so as to carry the division of the two ends of the fountain up above the member 32 and prevent ink leakage from one end of the fountain to the other. The blades 51 seal to the doctor blades 9, thus closing in the fountain on the doctor side completely except for the small gaps necessary for the doctor blade reciprocation. The similar closures on the doctor side at the ends of the cylinder 1 may be conventional and will not be described herein.

Ink may be supplied to the two ends of the fountain 60 and circulated between them and the ink reservoirs in any appropriate way, utilizing the usual openings 55 (Figure 2) for this purpose.

What is claimed is:

1. In a rotary intaglio printing machine, and in combination, a printing cylinder having a section of reduced diameter and a printing surface to each side thereof, a fountain comprising ends walls, side walls and a bottom, bearings at the ends of the fountain supporting the cylinder therein, partition means in addition to the said bottom and side walls in sealed relation to the reduced diameter section of the cylinder in sealed relation also to the said bottom and side walls, and divid-

ing the fountain into two separated compartments for inking the respective printing surfaces, a doctor mechanism comprising a reciprocal doctor to each side of the partition, and a cover under the doctors fitting the partition means and having an upwardly extending partition wall positioned between the two said doctors.

2. The combination according to claim 1, in which the partition means include arcuate flanges overlapping the cylinder printing surfaces and the cover partition wall has a shield fitting the partition means and covering the ends of the doctors.

3. In a rotary intaglio printing machine, and in combination, a printing cylinder having a section of reduced diameter and a printing surface to each side thereof, a fountain comprising end walls, side walls and a bottom and partition means in addition to the said bottom and side walls in sealed relation to the reduced diameter section of the cylinder in sealed relation also to the said bottom and side walls, for dividing the fountain into two separated compartments for inking the respective printing surfaces, the partition means comprising a sealing ring split in the horizontal axial plane of the cylinder and surrounding the reduced diameter section of the cylinder and a similarly split partition holding and in sealing engagement with the sealing ring.

4. In a rotary intaglio printing machine, and in combination, a printing cylinder having a section of re-

duced diameter and a printing surface to each side thereof, a fountain and partition means in sealed relation to the reduced diameter section of the cylinder for dividing the fountain into two separated compartments for inking the respective printing surfaces, the partition means comprising a sealing ring split in the horizontal axial plane of the cylinder and surrounding the reduced diameter section of the cylinder and a similarly split partition holding the sealing ring, packing means for sealing the ring to the reduced diameter section of the cylinder and for sealing the ring to the partition, a fitting for introducing lubricant between the ring and the partition and channels through the ring for supplying lubricant to its inner surface.
